Primary Examiner — Vy N Koenig*Assistant Examiner* — Omeed Agilee(74) Attorney, Agent, or Firm — Pauly, DeVries, Smith & Deffner LLC(57) CLAIM

The ornamental design for a bottle, as shown and described.

DESCRIPTION

FIG. 1 is a front and top perspective view of a bottle showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines in the drawings depict portions of the bottle that form no part of the claimed design.

1 Claim, 4 Drawing Sheets(56)
